CONVEYER STRUCTURE

Hermann S. Bogaty, Philadelphia, Pa., assignor to
Proctor & Schwartz, Incorporated, Philadelphia, Pa., a corporation of Pennsylvania

Original application August 3, 1933, Serial No.
683,529. Divided and this application June 15,
1934, Serial No. 730,837

9 Claims. (Cl. 198—181)

This invention relates to conveyor structure particularly adaptable for use in an improved apparatus for carrying out an improved process for blending and conditioning tobacco as disclosed in the applicant's copending application Serial No. 683,529, filed August 3, 1933, and of which the present application constitutes a division.

The structure forming the subject matter of the present application is particularly adapted for use in conditioning tobacco which has been formed into bundles each containing a predetermined number or quantity of leaves bound together at their stem ends, forming a head from which the leaves extend in more or less loose relation to each other.

In blending tobacco, to provide a mixture containing desirable qualities of two or more different varieties in correct proportions, it is customary to employ a long flat continuously moving endless belt conveyor comprising an upper carrying run and a lower idle return run disposed in vertically spaced relation to each other, the belt passing around suitable drums or pulleys at each of the opposite ends of the two vertically spaced runs of the conveyor.

Substantially one-half of the carrying run of the conveyor, toward one end thereof, is at all times disposed within a conditioning chamber while the remainder of the carrying run of the conveyor is out in the open and extends beyond the receiving end of the conditioning chamber, to provide a loading and/or blending station in the apparatus.

The several varieties of tobacco to be blended are contained in hogsheads or other suitable receptacles disposed along the blending or loading station, adjacent the conveyor. From the different receptacles attendants take predetermined numbers of bundles of the different tobaccos and place them in flat superposed and overlapping relation to each other on the conveyor belt, as it passes by the sub-stations occupied by the respective attendants.

The loaded portion of the conveyor then passes into the conditioning chamber, wherein the tobacco is subjected to circulating currents of moisture-laden air by which the dry and more or less brittle tobacco leaves are softened and prepared for subsequent processing and from which the mixture is discharged into a hopper or on to another conveyor for transportation to the apparatus by which the next step in the processing of the blended mixture is accomplished.

The capacity of such a blending and conditioning apparatus is objectionably low, due to the

necessity for keeping the layer of superposed horizontally disposed and overlapping tobacco leaves relatively thin on the conveyor, in order that the conditioning medium will penetrate to the center of the laminated layer.

Penetration to the center of the layer is at the best greatly retarded, and in thick layers prevented, by the overlapping relation of the superposed leaves, the uppermost of which presents a baffle, barrier or shed to downwardly moving moisture-laden air currents and the undermost of the overlapping leaves presents a similar barrier to upwardly moving moisture-laden air currents, whereby the moisture is carried to and around the sides of the conveyor. Laterally moving air currents are undesirable because of their tendency to blow the leaves off the conveyor and to break the brittle leaves and scatter them on the conveyor so that the proportions of the different tobaccos at different places on the conveyor would not be uniform.

The principal object of the present invention is to provide a conveyor structure which will lend itself to increasing the capacity of the blending and conditioning apparatus and to the attainment of quick and substantially uniform penetration of the mass of leaves assembled on the conveyor, by the conditioning medium, by making it possible to arrange the leaves in substantially parallel vertical relation to each other for the passing of the conditioning medium through the mass of leaves in a direction lengthwise of the leaves.

The bundles of leaves are preferably disposed on the conveyor with the heads extending downwardly and the leaves extending upwardly therefrom, and the conditioning medium is passed upwardly through the mass of leaves, in order that the conditioning medium may penetrate all portions of the assembled mass substantially simultaneously by passing between the leaves contained in each bundle in its movement lengthwise of the leaves, which is made possible and facilitated by the provision of the especially constructed conveyor forming the subject of the present invention which in its preferred form comprises a continuous series or train of rectangular box-like containers or chambers composed of perforated metal plate or wire mesh fabric stretched on a suitable framework, each container including a substantially flat normally horizontal base and top and relatively fixed back and side walls, while the front of each container is provided with hinged doors by which a predetermined number of bundles of leaves may be

confined in relatively close lateral and more or less loose abutting relation to each other in the container, with the heads of the bundles resting on the horizontal base.

5 In order to facilitate loading and unloading of the containers said containers are connected to each other in a manner to permit relative tilting of the containers, first in one direction transversely of the normal longitudinal path of movement of the train for loading purposes, then in an opposite transverse direction for discharging the mass from the interior of the containers.

By increasing the linear foot capacity of the conveyer and by passing the conditioning medium lengthwise of the leaves through the mass, the length of the conditioning chamber may be proportionately shortened; and by providing the series of containers in a train the conveyer, instead of running in a vertical plane as described above, is permitted to be run in a horizontal plane; and the return run of the conveyer, instead of passing idly through or under the conditioning chamber, passes around and to one side of the conditioning chamber, whereby the return run is utilized for loading and unloading thereby placing the loading or blending station at the one side of the conditioning chamber instead of its being at and extending a considerable distance beyond the one end of the conditioning chamber as above noted. Thus the total length of the conveyer including the carrying and return runs, is reduced to substantially one-half or less than one-half of the total length of the conveyers of the prior art, which constitutes a considerable saving of expense relative to the initial installation and subsequent maintenance.

The construction of the apparatus will be fully disclosed hereinafter, reference being had to the accompanying drawings, of which:

Fig. 1 is a diagrammatic plan view of the preferred lay-out embodying the conditioning chamber and the loading and unloading stations at the one side thereof;

Fig. 2 is a diagrammatic side elevation of the apparatus shown in Fig. 1;

Fig. 3 is a transverse sectional elevation taken on the line 3—3, Fig. 2;

Fig. 4 is a transverse sectional elevation taken on the line 4—4, Fig. 2;

Fig. 5 is a fragmentary longitudinal sectional elevation taken on the line 5—5, Fig. 1;

Fig. 6 is an enlarged plan view of one of the rectangular containers of which the conveyer is composed;

Fig. 7 is a front elevation of the container shown in Fig. 6;

Fig. 8 is a side elevation of the container shown in Fig. 6;

Fig. 9 is a fragmentary sectional elevation showing one of the containers of Figs. 6, 7 and 8 as being tilted outwardly to discharge the contents of the container and the means for opening the doors of the container;

Fig. 10 is a fragmentary front elevation of the container shown in Fig. 9;

Fig. 11 is a detail plan view of the door-locking mechanism;

Fig. 12 is a front elevation of the mechanism shown in Fig. 11;

Fig. 13 is a plan view of an automatic means for closing the doors of the conveyer baskets; and

Fig. 14 is a sectional elevation taken on the line 14—14, Fig. 13.

75 The apparatus shown in Figs. 1 to 5 inclusive

comprises a casing 1 including a bottom or floor 2, side walls 3 and 4 and a roof 5, which collectively form a chamber 6 through which tobacco is conveyed for conditioning.

Extending completely through the casing 1 from end to end thereof are inner and outer rail sections 11 and 12 of a conveyer-supporting track 10, as shown in Figs. 1 and 2. The conveyer track 10 also comprises inner and outer rail sections 11a and 12a which are disposed outside and to one side of the casing 1. The outer rail sections 12, 12a of the track 10 are connected at the opposite ends of the casing 1 by curved sections 13 and 14 respectively. The inner rail sections 11 and 11a of the track 10 terminate adjacent the opposite ends of the casing 1, in line with the pitch circles of sprocket wheels 15 and 16 which are disposed in horizontal planes and rotate about vertically extending axes of drive shafts 17 and 18, to which the sprocket wheels 15 and 16 are respectively secured.

Running on and supported by the rails 11, 11a and passing around the sprockets 15 and 16 is an endless conveyer chain 20, which, as illustrated in Fig. 7, comprises a series of links 21 having male and female ends 22 and 23 respectively, which are adapted to be connected to the ends of the adjacent links, to complete the endless chain 20, by vertically extending pintles 24.

Each of the links 21 is provided with a pair of 30 supporting rollers 25 rotatably mounted in the link and adapted to ride on the upper surfaces of the rails 11, 11a, and on horizontal flanges 15a and 16a of the sprockets 15 and 16 respectively, which are disposed in the same horizontal plane 35 as the rails 11, 11a of the track 10, whereby the chain 20 will travel at all times in a horizontal plane as it passes along the rails 11, 11a and around the sprockets 15 and 16.

Each of the links 21 carries one of the rectangular containers into which the tobacco is placed for conditioning. Each container 30 comprises a rigid skeleton frame 31 including a base 32, a top 33, a back 34, sides 35 and 36 and a front 37. The top, bottom, back and sides of the container 30 are closed with wire mesh screen or perforated plate permitting free circulation of the conditioning medium through the container as the container is conveyed through the casing 1.

The front 37 of the container is open and is adapted to be closed to confine the tobacco within the interior of the container by doors 40, 40 which are hinged to the front 37 of the container 30 at 39, 39. The interior of the container 40 is divided in half, to form compartments 30a and 30b, by a transversely extending perforated plate or wire mesh partition 38, extending from the back 34 to the front 37 of said container. Access to the said compartments 30a and 30b may be had by opening the doors 40, 40 which respectively close the said compartments 30a and 30b at the front thereof.

Springs 41, 41 each having one end secured to one of the pivots 39 and the opposite end bearing against the inside of the frame of each of the doors 40 tends to swing the doors open at all times, such tendency normally being resisted and the door being locked in container-closing position by a pin 42 projecting downwardly from each of the frames of the doors 40 and engaged by a cam surface 43 of a latch 44 which is pivoted at 45 to the underside of the bottom 32 of the container 30. The latch 44 is provided with a handle 46 adapted for swinging the latch about its pivot to engage the cam surface 43 with the pin 42, for 75

rigidly locking the door in a closed position. The latch 44 is also provided with a rearwardly extending arm 47 provided with a downwardly extending lug 47a adapted to engage a latch-releasing cam fixed in and at a predetermined position along the track 10, as will be hereinafter described.

Each container 30 is provided with a pair of depending hinge lugs 48 which are pivotally connected to hinge lugs 49, 49 carried by each of the chain links 21, by pivot pins 50, 50.

Projecting downwardly from the central front portion of the bottom frame 32 is a bracket 51 in which is secured a stud or axle 52 for rotatably receiving a roller or wheel 53 which is adapted to ride on the outer rails 12 and 12a of the track 10.

The loading of the containers 30 is accomplished at a loading station D along a section of that portion of the track 10 which is disposed outside the casing 1, intermediate the opposite ends thereof. The receptacles containing the different varieties of tobacco to be blended are disposed adjacent the track 10 along the loading station D to be readily accessible to the attendants loading the conveyer consisting of the train of containers 30, 30.

Each of the containers 30 is adapted to be tilted rearwardly, as indicated in Fig. 3, in one direction transversely of the track 10 and for this purpose a portion 12b of the outer rail 12a is elevated above the horizontal plane of the rail section 12. The portion 12b of the said outer rail is provided with an inturned flange 12c disposed above and overhanging the tops of the container rollers 53, to prevent tilting of the containers 30 beyond a predetermined angle.

The containers 30 are tilted rearwardly for the purpose of facilitating the loading of the compartments 30a and 30b of each container with the bundles of tobacco leaves from the various receptacles disposed along the loading station D. In loading the containers 30 the tobacco leaves of the several varieties are laid in an upright position against the rearwardly inclined back wall 34 of the container with the heads of the bundles resting on the correspondingly rearwardly tilted bottom 32 of the container. The bundles are loosely packed in the container in this manner until full, whereupon the doors 40, 40 are closed and locked by the latches 44 by the attendant nearest the far end d of the loading station D, or automatically by means located near the said end of the loading station, as the train of containers moves in the direction of the arrow a, Fig. 1.

The outer rail 12e is inclined as illustrated at 12d from the level of the one end of the elevated portion 12c to level of the curved end section 13 of said outer rail, said curved section being in such a plane relative to the horizontal plane of the flange 15a of the sprocket 15 as to move the containers from the rearwardly tilted positions shown in Fig. 3 to the substantially horizontal or level positions shown in Fig. 4, as the sprocket 15 rotates and moves the train of conveyer containers from that portion of the track 10 outside the casing 1 on to that portion of the track within the casing 1, said containers entering the casing 1 at the end E thereof and continuing in the level positions completely through the said casing, from which the containers successively emerge at the end F thereof.

As the containers are carried around the sprocket 16 the curved end 14 of the outer rail

of the track 10 begins to fall away vertically and inwardly toward the axis of the sprocket, as indicated at 14a in Figs. 1 and 2. The said curved portion 14a of the outer rail of the track 10 merges with a compound curved portion 12e of the outer rail 12a, which in turn merges into a vertically disposed portion 12f of the rail.

As the containers move around sprocket 16 the wheels 53 of the containers ride the inwardly descending portion 14a of the curved end 14 of 10 said rail, which causes the containers to tilt outwardly as indicated in Figs. 2 and 5, and as the movement of the containers continues and the wheels 53 ride the compound curved portion 12e of the said outer rail and on to the vertical portion 12f thereof the said containers 30 are tilted to a position substantially at 90° with respect to the normal level position in which they travel through the casing 1, such position being clearly illustrated in Fig. 4.

As each container moves into a position wherein its roller 53 is in engagement with the vertical portion 12f of the outer rail 12a, the doors 40 of the containers 30 are automatically opened by the lugs 47a of the latches 44 engaging an inclined cam 55, which is supported in a fixed position adjacent the vertical portion 12f of the outer rail by a bracket 56, as clearly indicated in Figs. 9 and 10. As the latches 44 successively release the doors 40 of the containers 30 the doors 40 are swung open to the position shown in Fig. 4 by the springs 41 whereby the entire contents of each compartment of each container 30 is discharged from the container, in the present instance on to the carrying run of a belt conveyer 60 by which 35 the mixture of tobacco within the containers is transported to the apparatus for accomplishing the next step in the processing of the mixture.

The doors 40 are each maintained in an open position substantially in alignment with the side 40 walls 35 and 36 of the container by the springs 39 pressing the said doors against stop lugs 57 formed on the front 37 of the frame of the container.

With the doors of the container open, the said 45 containers then pass from the discharging station G to the receiving end d' of the loading station D, said containers being moved from the extreme forwardly tilted position in Fig. 4 to the rearwardly tilted loading position shown in Fig. 3, 50 by the wheels 53 riding an outwardly and upwardly bent compound curved portion 12g of the outer rail 12a.

The sprockets 15 and 16, either or both, may be driven by any suitable motive power through 55 any suitable type of power transmission, for driving the chain 20 continuously or intermittently, as occasion may demand or as may be desired, for carrying the train of conveyer containers along the course and through the cycle of movements described above.

In a foregoing portion of the specification the doors 40, 40 of the containers 30 are described as being closed by the attendant nearest the far end 65 of the loading station D, or by automatic means located near the said end of the loading platform. Such means is clearly shown in Figs. 13 and 14, wherein, as the containers 30 move along the track 10 in the direction of the arrow a, Fig. 1, and near the end d of the loading station D, with 70 the doors 40 of the containers open, the ends 47a of the arms 47 of the latches 44 engage a flared end 125a of a rail or angle bar 125 which is rigidly mounted adjacent and extends parallel to the rail 12a of the track 10, see Figs. 22 and 23, to 75

first assure the positions of the latches correctly for passage of the locking pins 42 on the doors 40 into position to be engaged by the cam surfaces 43 of the latches.

5 The leading door 40a, i. e. the door toward the right side of each container is closed by the door engaging and outwardly flared end 126a of a rail 126 rigidly secured to, adjacent and above the rail 12a of the track 10.

10 The trailing door, i. e. the door toward the left side of each container is provided with a lug or arm 127, which, as the container moves along the track 10, engages a flared end 128a of a fixed rail 128, paralleling the rails 12a and 125, which 15 swings the door 40b into a closed position.

15 The doors are held in their closed positions by the rails 126 and 128 until the container reaches the extreme end *d* of the loading station D, whereupon the outer ends of the latch arms 46 engage 20 a flared end 129a on a spring-pressed plate 129, which swings the latches 44 into their door-locking positions before described.

25 The automatic door-closing attachment above described is preferable to the manual closing of the doors, however, the doors may be closed manually and the automatic closing attachment provided as a safety means should the attendant for some reason fail to close one or more of the container doors, and in any event the spring-30 pressed plate 129 will function to press the latches 44 firmly into their door-locking positions before the containers are tilted forwardly from their rearwardly inclined loading positions to their normal horizontal or level positions in which they 35 travel through the conditioning chamber.

35 I claim:

1. A blending and conditioning apparatus comprising a casing providing a conditioning chamber, a conveyer track extending in a horizontal 40 plane longitudinally through the conditioning chamber and outside the casing along and adjacent one side thereof to provide a loading station, a conveyer operating on said track and comprising a train of operatively connected substantially 45 rectangular containers each provided with a side door for loading and unloading of the containers, a depression in one side of the track at one end of the loading station for tilting the containers transversely to discharge the contents therefrom, 50 and an elevation along said side of the track for tilting the containers in an opposite transverse direction along said station for loading of the containers.

55 2. A blending and conditioning apparatus comprising a casing providing a conditioning chamber, a conveyer track extending in a horizontal plane longitudinally through the conditioning chamber and outside the casing along the adjacent one side thereof to provide a loading station, a conveyer operating on said track and comprising a train of operatively connected substantially 60 rectangular containers each provided with a side door for loading and unloading of the containers, a depression in one side of the track at one end of the loading station for tilting the containers transversely to discharge the contents therefrom, 65 means for opening the container doors to permit discharge of the contents, and an elevation along said side of the track for tilting the containers in an opposite transverse direction along said station for loading of the containers.

70 3. A blending and conditioning apparatus comprising a casing providing a conditioning chamber, 75 a conveyer track extending in a horizontal plane

longitudinally through the conditioning chamber and outside the casing along and adjacent one side thereof to provide a loading station, a conveyer operating on said track and comprising a train of operatively connected substantially rectangular containers each provided with a side door for loading and unloading of the containers, a depression in one side of the track at one end of the loading station for tilting the containers transversely to discharge the contents therefrom, 10 means for opening the container doors to permit discharge of the contents, an elevation along said side of the track for tilting the containers in an opposite transverse direction along said station for loading of the containers, means for maintaining the doors in an open position for manual closing at a desired point along the loading station, and means for locking the doors in a closed position during travel of the containers through the conditioning chamber. 15

20 4. A blending and conditioning apparatus comprising a casing providing a conditioning chamber, a conveyer track extending in a horizontal plane longitudinally through the conditioning chamber and outside the casing along and adjacent one side thereof to provide a loading station, a conveyer operating on said track and comprising a train of operatively connected substantially rectangular containers each provided with a side door for loading and unloading of the containers, 25 a depression in one side of the track at one end of the loading station for tilting the containers transversely to discharge the contents therefrom, means for opening the container doors to permit discharge of the contents, an elevation along said side of the track for tilting the containers in an opposite transverse direction along said station for loading of the containers, means for maintaining the doors in an open position for manual closing at a desired point along the loading station, 30 safety means for positively closing said doors at a predetermined point along said loading station, and means for locking the doors in a closed position during travel of the containers through the conditioning chamber. 35

45 5. A blending and conditioning apparatus comprising a casing providing a conditioning chamber, a conveyer track extending in a horizontal plane longitudinally through the conditioning chamber and outside the casing along and adjacent one side thereof to provide a loading station, a conveyer operating on said track and comprising a train of operatively connected substantially rectangular containers each provided with a side door for loading and unloading of the containers, 50 a depression in one side of the track at one end of the loading station for tilting the containers transversely to discharge the contents therefrom, means for opening the container doors to permit discharge of the contents, an elevation along said side of the track for tilting the containers in an opposite transverse direction along said station for loading of the containers, means for maintaining the doors in an open position, means for automatically closing said doors at a predetermined point along the loading station, and means for locking the doors in a closed position during travel of the containers through the conditioning chamber. 55

60 6. The combination of a continuous conveyer track disposed in a general substantially horizontal plane, a series of individual containers connected as a continuous train operating on said track and provided respectively with side openings for loading and unloading of the conveyer, 65

5

doors respectively closing said openings, said track comprising a pair of container-supporting rails having relatively depressed and elevated portions for tilting the containers transversely of the track to facilitate and effect loading and unloading of the containers through said side openings, and means adjacent said depressions for opening said doors.

7. A conveyer structure comprising a train of normally vertical containers arranged to travel in a substantially horizontal path and each having a side opening for loading and unloading thereof, a door normally closing said opening and pivoted on a vertical axis substantially parallel to and adjacent the vertical edge of said side opening, means connecting said containers for relative lateral rocking motion with respect to said path, means for rocking the containers from said normal vertical position to a substantially horizontal position with the door closed opening underneath, and means for opening said door while a container is in said horizontal position to effect discharge of the contents thereof through said side opening and substantially perpendicular to the path of movement of said train.

8. A conveyer structure comprising a train of normally vertical containers arranged to travel in a substantially horizontal path and each having a side opening for loading and unloading thereof, a pair of doors normally closing said opening and pivoted on vertical axes substantially parallel to and adjacent opposite vertical edges

of said side openings respectively, means connecting said containers for relative lateral rocking motion with respect to said path, means for rocking the containers from said normal vertical position to a substantially horizontal position with the door closed opening underneath, and means for opening said doors while a container is in said horizontal position to effect discharge of the contents thereof through said opening and substantially perpendicular to the path of movement of said train.

9. A conveyer structure comprising a train of normally vertical containers arranged to travel in a substantially horizontal path and each having a side opening for loading and unloading thereof, a door normally closing said opening and pivoted on a vertical axis substantially parallel to and adjacent the vertical edge of said side opening, means connecting said containers for relative lateral rocking motion with respect to said path, means for rocking the containers from said normal vertical position to a substantially horizontal position with the door closed opening underneath, means for maintaining said door in its closed position, and means for releasing said door to permit opening thereof while a container is in said horizontal position to effect a discharge of the contents thereof through said opening and substantially perpendicular to the path of movement of said train.

HERMANN S. BOGATY.
